UNITED STATES PATENT OFFICE.

HENRY SCHWARBER, OF WEEHAWKEN, NEW JERSEY, ASSIGNOR TO INFLEXIBLE CO.,
OF WEST NEW YORK, NEW JERSEY.

DESIGN FOR A WAIST-FRONT.

46,551.

Specification for Design.

Patented Oct. 13, 1914.

Application filed June 30, 1914. Serial No. 848,316. Term of patent 3½ years.

To all whom it may concern:

Be it known that I, HENRY SCHWARBER, a citizen of the Republic of Switzerland, residing at Weehawken, in the county of Hudson and State of New Jersey, have invented a new, original, and ornamental Design for Waist-Fronts, of which the following is a specification, reference being had to the accompanying drawing, forming part thereof.

The figure is a plan view of a waist front showing my new design.

I claim:

The ornamental design for a waist front as shown.

HENRY SCHWARBER.

Witnesses:

CONRAD KELLER,
THEODORE STROEHLLEN.
